F. POKORNY

FLUID CONTROL MEANS FOR MOTORS

Original Filed May 1, 1920

UNITED STATES PATENT OFFICE.

FRANK POKORNY, OF MAMARONECK, NEW YORK, ASSIGNOR, BY DIRECT AND MESNE ASSIGNMENTS, OF ONE-HALF TO FRANCIS W. KEEGAN, OF NEW YORK, N. Y.

FLUID-CONTROL MEANS FOR MOTORS.

Application filed May 1, 1920, Serial No. 378,190. Renewed September 18, 1924.

To all whom it may concern:

Be it known that I, FRANK POKORNY, a citizen of the United States, and resident of Mamaroneck, in the county of Westchester 5 and State of New York, have invented certain new and useful Improvements in Fluid-Control Means for Motors, of which the following is a specification.

This invention relates to fluid supply control means for internal combustion engines and my present improvements are directed to certain novel means now incorporated by me in the structural organization comprised in my earlier patent application Serial No. 15 338,747, whereby said organization is rendered more effective in its operation.

Said earlier application includes a gravity return valve which opens to permit the passage of fluid in larger volume to satisfy 20 the demands of the engine as its speed increases, the valve being actuated by the suction pull of the engine against gravity plus a suction drag to which said valve is subjected, wherein the influence of the suction 25 drag force is more pronounced during the earlier portion of the valve's opening movement.

Therefore my invention has been devised for the purpose of providing automatic 30 means, actuated by the aspiratory tension of the engine, to maintain a constant vacuum condition in the manifold at all engine speeds, and to control the area of the fluid passage between the carburetor and intake 35 to thereby regulate the siphonage effect upon the fuel nozzle, so that the varying pressure in the manifold will draw fuel in proportionate quantities from the nozzle to provide satisfying fuel and air mixtures for 40 all rates of engine speed.

This means that with the smallest opening to the fuel mixture passage the vacuum will be high in the passage and consequently air will enter the passage at high speed though 45 in relatively small volume, and therefore will have the effect of drawing in fuel from a small fuel nozzle in atomized condition but in quantity suited to the engine requirements at low speed.

50 Briefly expressed, my invention consists of means included in the passage from the carburetor to the intake manifold, to normally restrict the size of said passage so that at low engine speeds the engine tension

will be relatively high, enabling it to maintain a manifold pressure low enough to siphon liquid fuel from the carburetor nozzle in sufficient quantity to form, with the aspirated air, fuel mixture suited to low 55 engine speed requirements.

The control means which permits and regulates the increase in area of the fuel mixture passage from the carburetor to the manifold comprises a free valve which operates in a vacuum chamber that is subjected to the varying pressures in the manifold, said valve being raised a greater or less extent and thereby increasing the size of the fuel mixture passage more or less, according to the degrees of pressure variation in the manifold, and hence according to the changes in engine speed.

As the engine speed increases the pressure in the manifold is correspondingly reduced 70 and thus the siphonage effected upon the fuel nozzle is increased, causing the liquid fuel to issue more freely; and as a function of the lower pressure in the manifold the free valve operates to increase the area of 75 the passage clearance, while greater siphonage effect is applied to the fuel nozzle and thus an increased flow of fluid is provided for the higher engine speeds, and the proportionality of the mixture is also preserved. 80

The free valve opens more slowly at first because the clearance which comprises the communication between the fluid passage and the vacuum chamber remains constant 85 in area during the initial portion of its rise, but beyond a certain point in that rise said clearance enlarges and then the reduced pressure of the manifold becomes more effective upon the vacuum chamber and permits the pressure of incoming fluid mixture 90 to open the valve more rapidly.

Also I provide clearance means at the opposite end of the valve, in communication with the vacuum chamber, to thereby enable the lowered pressure to function as a drag 95 force in retarding the valve operation.

Other features and advantages of my said invention will hereinafter appear.

In the drawing:—

Figure 1 is an elevation, partly in section, 100 of a fluid passage including my improved control means.

Fig. 2 is a partial sectional view thereof with an added feature.

Fig. 3 is a similar view with a modification.

Fig. 4 is a similar view, with a further modification.

5 Fig. 5 is a similar view, with a still further modification.

Fig. 6 is a section on the line 6—6 of Fig. 3, and

10 Fig. 7 is a section on the line 7—7 of Fig. 2.

In the drawing, let 1 indicate a tube which is in communication with a carburetor (not shown), and let 2 indicate a tube which communicates with or forms part of an engine 15 intake manifold. The tubes 1 and 2 are connected, as by flanges, 3, 4, by means of an intermediary, cylindrical casing 5, which serves as a duct or passage for the fuel mixture flowing to the engine.

20 In tube 1 I have shown a throttle valve 6, which however may be otherwise located. The elements of the control means, to be hereinafter described, may be snugly contained within the casing 5, that may be a casting, as by a threaded annulus 7 that is screwed into the lower end of casing 5, the annulus 7 itself forming a supporting base 25 for said elements.

25 In this manner, by removing the bolts 8 that unite flanges 3, 4, with the flanges 9 of casing 5, the latter, with the contained control elements, may be bodily removed from its line position.

30 Fitting within the lower portion of casing 5, and supported on the annulus 7 is a cylindrical member having the outer concentric wall 10, the relatively shorter, inner concentric wall 11, in spaced relation with wall 10, and the concentric base 12 which is common to both said walls and forms the lower 35 closure of a concentric space or chamber 13 that is bounded circularly by said walls 10 and 11. Also the wall 11 forms the lower portion of the fluid passage to the engine.

40 45 Carried by arms 14 that are borne by the wall 11 is a centrally disposed nozzle member 15, which is provided with an axial orifice 16, for the flow of a restricted volume of fluid; and, as also shown in my said co-pending application, a concentric passage portion 17 extends up from the wall 10, carrying the inwardly directed arms 18, which support a centered cone 19 in the path of the fluid ascending to the manifold.

50 55 The portion 17, which has a shoulder or under surface 20 overhanging the concentric space 29, which comprises a vacuum chamber, is provided with a lower cylindrical portion 21 as part of its inner surface, said 60 surface continuing upwardly from portion 21, at an outward inclination, to a point near the upper end of portion 17, where it has a re-entrant incline.

65 The outer conformation of nozzle member 15 is that of a double cone, having the upper

conoidal portion 22, and the lower, inverted conoidal portion 23, the junction of said conoidal portions representing the major diameter of the member 15, whose periphery, in the horizontal plane of said major diameter, co-acts with a tubular valve member 24 for the passage of regulated supplementary quotas of fluid in a manner to be hereinafter described.

70 The tubular valve 24 has an intermediary 75 or body portion, with an upward skirt-like portion 25, and a lower, skirt portion 26, the skirt 25 extending from the most restricted diametral part of said body portion, while the skirt 26 depends from the major diametral part thereof.

75 It is at the most restricted diametral part of the valve body portion that said valve is contiguous to the nozzle member 15, at the major diameter thereof, because it is the 80 function of the valve to rise and recede from that location to thereby provide for the passage of fluid in regulated volume.

85 Interiorly of the said restricted diametral part of the valve body portion, the latter is 90 given a downward and outward inclination, designated as inclined surface 27, that lies above the upper peripheral edge 11a of wall 11. Valve 24, at the outer surface of its 95 body portion and skirt 26 is in slidable relation with wall 10, and said skirt 26 has at its lower end an inturned concentric flange 28, whose inner periphery is located in slid- 100 able relation to the wall 11, so that the space 13 is reduced in area by the thickness of skirt 100 26 and flange 28 therein, and said reduced space is bounded by wall 11, skirt 26 and flange 28. Therefore valve 24 is normally seated by gravity with its flange 28 upon base 12, and the clearances between the valve 105 and wall 10 and between the inner periphery of flange 28 and wall 11, though said clear- 110 ances are sufficient only to permit slidable movement to the valve, also serve another function which will be treated of herein- 115 after.

120 The vacuum chamber 29 is provided for the operation of valve 24 under the aspiratory tension of the engine, said chamber being bounded by wall 10, skirt 25, surface 20, and an opposed surface 30 which comprises the upper surface of the valve body portion, whereby the rarification and suction pull in chamber 29, plus the impinging pressure of ascending fluid against the inclined surface 27, tend to raise said valve.

125 As explained in my said co-pending application, the suction pull of the engine takes effect in the chamber 29 through the clearance between the cylindrical portion 31 of skirt 25 and the surface 21, this clearance enlarging with the rise of the valve to a given point owing to the special formations of the skirt 25 and the portion 17, whereby the opening of valve 24 during the 130

low range of engine speed is slow, and is more rapid during the higher range of engine speed.

In the present application however I desire to particularize the novel means whereby the sluggish opening of the valve during the low R. P. M. range is accentuated, or whereby the weight of the valve as a retarding influence to its rising movement is, as it were, more materially increased than by the means set up for the same purpose in my said co-pending case.

Thus the suction drag which I have previously relied upon is rendered more efficient in my present improvement, because the flange 28, opposed to the base 12, is subject to suction pull exerted through the clearances that exist between wall 10 and skirt 26, and between wall 11 and the peripheral surface of flange 28, and the entire bottom surface of valve 24 presents considerable effective area to the influence of the drag force. The short passage for air flow presented by the latter clearance, it will be appreciated, greatly limits the friction to which such air flow is subjected.

In the operation of the device, when fluid is being aspirated past the valve 24 as well as through orifice 16, some rarefaction occurs in space 13 due to the fluid flow past edge 11^a of wall 11, but the degree of lift force thus exerted is incommensurate with the degree of suction drag applied through the reduced clearance. Besides, the available pressure area of incline 27 is reduced by the location of wall 11, which exposes only the upper portion of said incline to impingement by the ascending volume of fluid.

With the drag force exerted to retard the valve lift its opening movement is rendered desirably sluggish during the early range of engine speeds, so that the volume of fluid that passes said valve is relatively small, and it is not until a considerable increase in engine speed has been attained and the clearance to vacuum chamber 29 has enlarged to a point where the suction pull exerted in said chamber is much more effective that the drag is preponderated by the suction pull sufficiently to cause the valve to then lift with appreciably greater progressive rapidity.

The additional feature illustrated in Figs. 2 and 7 consists of a duct 32 which extends through valve 24 from a point adjacent to the fluid path between the contiguous portions of the valve and member 15, said duct continuing into a vertical channel 33 that extends down the outer surface of skirt 26 to the bottom thereof, thus forming a vent through which suction created by the fluid flow past the valve materially amplifies the drag force applied to the valve base.

Also, in Figs. 3 and 6 a modified vent means is shown as comprising an orifice 34

provided in portion 17 in communication with a vertical channel 35 extending down the rear surface of said portion and down the rear surface of wall 10, to the base 12, where it communicates with an orifice 35 extending horizontally to a point beneath the valve 24, and to a vertical opening, regulated by needle valve 36, for the application of suction drag force to the valve base.

Instead of, or in addition to the means previously described for amplifying the degree of suction drag force provided for retarding the lift of the valve, I may employ means in conjunction with the vacuum chamber 29 to limit the suction lift force applicable thereto during a portion of its opening movement. Thus, in Fig. 4 I have shown said vacuum chamber 29 as having a vent composed of a series of tiny orifices leading to the atmosphere, so located as to be fully effective in nullifying a part of the suction effort until the valve has been raised to provide a given extent of opening, and thereafter becoming progressively less effective. The vent orifices, which extend through wall 10 and casing 5, are arranged to become ineffective in succession as the valve rises in the vacuum chamber, and, with the concomitant opening by the valve of the fluid passage on account of accretion in engine tension under the acceleration of engine speed, the suction pull becomes progressively stronger in said vacuum chamber, and thus the valve is moved upwardly with progressively greater rapidity.

Still further I may provide similar vent orifices 37 (see Fig. 5) to open to the atmosphere the clearance between the valve bottom and base 12, at a point where the lift of the valve represents the upward limit of that lift with respect to the low range of engine speed, whereby the suction drag force, from that point in the valve lift, becomes progressively less effective as the orifices 37 are successively uncovered in the valve movement.

Variations may be resorted to within the spirit and scope of my said invention, and parts thereof used without others.

I claim:

1. In fluid supply means for internal combustion engines, in combination, a control valve, means whereby said valve is caused to open under the suction pull created by the aspiratory operation of the engine, a lower skirt portion for said valve, a flange for said skirt to enlarge its area, a concentric chamber in which said skirt portion operates, and means whereby the influence of the suction pull is exerted as a drag force upon said valve skirt and flange to retard the valve opening movement.

2. In fluid supply means for internal combustion engines, in combination, a control valve, means whereby said valve is caused to

open under the suction pull created by the aspiratory operation of the engine, a chamber in which said valve is operable, means of communication whereby said valve is subjected to a drag force, opposed to the lift force, by said suction pull, and vent means to modify the drag force.

3. In fluid supply control means for internal combustion engines, in combination, 10 a passage for fluid flow having a restricted portion, a control valve to co-act with said restricted portion, means whereby said valve

is caused to open under the suction pull created by the aspiratory operation of the engine, means of communication whereby 15 said valve is also subjected to drag force by said aspiratory operation, and vent means extending from a point adjacent said restricted portion to supplement the drag force.

Signed at the borough of Manhattan in the city, county and State of New York this 22nd day of April A. D. 1920.

FRANK POKORNY, Jr.

Certificate of Correction.

It is hereby certified that in Letters Patent No. 1,539,271, granted May 26, 1925, upon the application of Frank Pokorny, of Mamaroneck, New York, for an improvement in "Fluid-Control Means for Motors," errors appear in the printed specification requiring correction as follows: Page 2, line 21, after the word "located" strike out the period and insert a comma and the words, *provided it is situated between the carburetor and fuel mixture passage*; page 3, after line 63, insert *The depression above the cone is by this vent communicated to the valve base, thereby supplying the additional drag force for restricting the valve opening until the preponderating suction pull has raised the valve sufficiently to enlarge the clearance at 21, 31. At varying engine speeds and loads there is a strangling effect produced at the passage between the valve and cone, causing the mixture to flow therethrough at high velocity with consequent drops in temperature and with re-atomization of the fuel, the particles whereof have the tendency to coalesce after partial atomization in the carburetor or upon passing the partly open throttle prior to reaching the valve passage*; and that the said Letters Patent should be read with these corrections therein that the same may conform to the record of the case in the Patent Office.

Signed and sealed this 30th day of June, A. D. 1925.

[SEAL.]

KARL FENNIG,
Acting Commissioner of Patents.
